PLATE OR SIMILAR ARTICLE

George L. Horton, Jr., Corning, and Mark R. Weitzman,
Elmira, N.Y., assignors to Corning Glass Works, Corning,
N.Y., a corporation of New York

Filed Nov. 15, 1967, Ser. No. 9,422

Term of patent 14 years

U.S. Cl. D44—15
Int. Cl. D7—01

The figure is a top plan view of a plate of conventional configuration showing our new design.

The color code shown in the drawing has been utilized to indicate color contrast, but without reference to a particular color.

We claim:

The ornamental design for a plate or similar article, as shown and described.
